(57) **CLAIM**

The ornamental design for a cable connector for lamp, as shown and described.

DESCRIPTION

FIG. 1 is a perspective view of a cable connector for lamp showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings are for the purpose of illustrating portions of the cable connector for lamp that form no part of the claimed design.
